BOX LABELING AND EDGING

Application filed July 18, 1928. Serial No. 293,548.

This invention relates to the attaching of labels and edging to cigar boxes and similar containers; and has for its principal object the provision of an improved combined label and edging, whereby the process of applying same to the cigar box is simplified and the cost of labor and materials is greatly reduced.

The problem of applying labels to cigar boxes involves a number of considerations and difficulties that are peculiar to cigar boxes for the reason that a number of practices have come to be established in the trade and for the additional reason that cigar boxes almost universally are so constructed that the end walls project above the front and rear walls so as to provide for the reception of a lid between such end walls and resting on the front and rear walls.

The customary practice existing at present in the finishing of cigar boxes generally involves the application of a separate label to each face or wall of the box. In addition thereto a number of separate edging strips are pasted on the various corners and edges of the box body. The labels and edging strips in common use at present may be printed in colors and may in addition thereto have embossed designs thereon. It is also a common practice to make one or both of labels on the end walls in a large number of colors and generally more fanciful designs which are frequently embossed, whereas the labels on the front and rear walls are not usually quite as elaborate. The application of the edging strips involves a number of operations. One long edging strip is folded around the lower edges of the box and pasted to the outer surface of the bottom and to the lower side of all walls of the box; another long strip is folded around three upper edges of the box body and pasted to the outer and inner surfaces of both ends and of the front thereof. Still another strip is pasted over the cloth hinge when in position on the box body. In addition to the above, four edging strips are pasted on the vertical corners of the box body.

The present invention is designed to eliminate the large number of strips and labels that are necessary in the practice of the old

method of finishing cigar boxes and for this purpose a combined label and edging is provided for each outer face of the box. The combined label and edging is so designed that it may be applied with labeling machinery with a minimum number of operations and in a much more accurate, neater and more expeditious manner than in the practice known hitherto.

It has been proposed to provide a combined unitary label and edging member or the like which comprises labels and edging for all sides and also the bottom of the box. It has been found, however, that in the application of such labels to cigar boxes difficulties arise partly due to the fact that dimensions of cigar boxes vary somewhat to accommodate different sizes of cigars. The old practice of applying edging strips which are separate from the labels has been designed in part to overcome this difficulty. When combined unitary label and edging strips which are designed to cover the bottom as well as the lateral faces of the box are utilized this difficulty is not overcome and such labels have to be printed and cut to accommodate different size cigar boxes. This difficulty is entirely overcome within reasonable limits by the combined labels and edging strips disclosed in the present application.

In view of the fact that as stated above it is common practice to provide more elaborate labels for the end walls than for the front and rear walls, the method of applying a unitary label to the bottom and all lateral faces of the box involves considerable additional expense when such method is attempted for such boxes. It has been found necessary in such cases to apply additional embossed or specially printed labels to the end faces of the box over the unitary label. This obviously involves an additional unnecessary waste and expense. In the present invention such waste and unnecessary expense of material and labor is eliminated.

To accomplish the above objects the present invention contemplates the use of only four independent units, each of which comprises a label for one lateral face of the box and the necessary edging strips for said face,

- all of these units cooperating with each other to finish the box with the minimum expenditure of material and labor. The use of such four combined labels with edging strips makes the system flexible in that the same set of labels may be applied to boxes varying in size. By the use of such four independent units the type of label for each unit may be varied with respect to the other and if desired one or both of the end labels may be printed in a larger variety of colors than the front or rear labels or vice versa, or any of them may be provided with embossed designs.
- While the drawings which constitute a part of the present application show three forms of the present invention, each modification embodies the same basic inventive ideas which will be clearly understood from the detailed description which follows hereinafter.
- The basic ideas, however, are explained at this point so that a reading of the specific construction of the various modifications will facilitate in the understanding of the principles of invention involved.
- One of the principles of invention in all modifications resides in the fact that the four combined units are divided into two groups, one group of two units being intended to be applied to the end walls of the box and the other group of two units being intended to be applied to the front and rear walls of the box. In all modifications shown in the drawings and described hereinafter the combined units in one group are so constructed that they necessitate the use of a cutting die to provide the notches or cut out portions, which make it possible to apply these units in such a manner as to properly cover those portions of the end walls which project above and overlie the front and rear walls. The other group of combined units is so designed that each unit is substantially oblong in shape and may be cut from strip material without the use of any cutting dies whatever, or if such dies are used, they may be of simple form. This reduces the cost of the preparation of the units considerably. The invention, moreover, makes it possible to prepare one or more units from one type of material and the remaining units from other types of material.
- An inspection of the drawings will show that in the preferred embodiment shown in Figs. 1 to 9, the end units correspond to the first group described above whereas the front and rear wall units correspond to the second group described above. In the embodiment shown on Sheet 3 of the drawings this relationship is reversed and the end units are of oblong shape whereas the front and rear wall units are provided with the cut out portions.
- In the modification appearing on Sheet 4 of the drawings, the end units are provided with cut out portions and the front and rear walls are substantially oblong in shape.
- Another principle of invention embodied

in all modifications resides in the fact that the set of combined units is so designed that it may be applied to cigar boxes of a plurality of sizes.

More specifically, each of the units in the one group, comprises a label for the corresponding wall and edging strips for all the corners of said wall as well as an edging strip which is intended to overlap and be applied to the adjacent portions of the adjacent walls. These portions are so cut and constructed that they will cover completely and neatly the portions of the end walls which project above the front and rear walls. Each unit in the second group comprises a label portion for the corresponding wall and edging strips for the upper and lower corners. As will be explained hereinafter the unit designed to be applied to the rear wall does not carry a complete edging strip for the upper edge.

The present application is a continuation in part of our application Serial No. 208,610, filed July 26, 1927, for box labeling and edging.

The following is a description of three modifications each embodying the basic principle of the present invention. It will be understood that still other modifications and changes may be made without departing from the spirit of the invention and without exceeding the scope of the claims.

Figure 1 is a perspective view of a cigar box of conventional form to which the preferred embodiment of the invention has been applied.

Figure 2 shows the combined label and edging for the front face of the box.

Figure 3 shows the combined label and edging for the rear face of the box.

Figure 4 shows the combined label and edging for each of the end walls of the box.

Figure 5 is a sectional view taken along the line 5—5 of Figure 1.

Figure 6 is a sectional view taken along the line 6—6 of Figure 1.

Figure 7 is a bottom plan view of the box shown in Figure 1.

Figure 8 is a detail view showing the manner in which the end labels are folded over a bottom corner of the box.

Figure 9 is a detail sectional view taken along the line 9—9 of Figure 1.

Figures 10 to 13 show a modified form of the invention in which Figure 10 shows a developed view of one of the end labels. Figure 11 shows a similar view of the front label and Figure 12 shows a similar view of the rear label and Figure 13 is a view similar to Figure 9.

Figures 14 to 17 show another modified form of the invention in which Figure 14 shows an end label, Figure 15 a front label, Figure 16 a rear label and Figure 17 a detail view similar to Figure 9.

In the preferred form of the invention as

shown in Figures 1 to 9 inclusive each of the end labels is provided integrally therewith with edging strips for the two adjacent vertical corners as well as for the two horizontal corners of the box. These end labels are therefore applied to the box first and the front and rear labels are cut to such a size as to cooperate with the vertical edging strips carried by the end labels.

10 The combined label and edging strip unit designed to cover the end walls of the box is shown in Figure 4 and comprises the label portion 21, a lower edging strip 22, vertical edging strips 23 and an upper edging strip 24. The dotted oblong 25 shown in Figure 4 is intended to indicate the face of the box to which the label is to be applied and the vertical dot and dash lines 26 indicate the thickness of the front and rear walls of the box.

15 20 The label portion 21 of the combined unit is preferably outlined by a printed oblong 27 which is so disposed that it falls well within the limitation of the area of the end wall 25 of the box.

25 In the old practice where a plurality of edging strips were applied to a cigar box it was common to provide such edging strips with printed insignia usually carrying the 30 trade name of the cigar or the name of the maker of the cigar. In order to closely imitate the appearance of the well established old form of cigar labels and edging, the combined unit 20 has similar insignia printed 35 thereon in the spaces indicated by the oblongs 28 in the edging strips of the combined unit.

40 In this particular form of embodiment illustrated, a line of heavy solid color 29 forming an oblong approximating the area of the 45 end face of the box is printed on the combined unit 20 and indicates approximately the registry of the label with the corners and edges of the end wall of the box. This line is extended horizontally at 30 to the vertical edges of the combined unit and the lines 31 are disposed somewhat below the top of this oblong so that the same may register with the corresponding lines on the front and the rear combined units as will appear from later descriptions of such units; the front and rear 50 units being shorter in height and therefore having their label portions of smaller vertical dimensions.

55 In order to facilitate the application of the combined units 20 to the end walls of the box and in order to provide for means for completely covering every portion of the box, cut out portions are provided so that each of the vertical edging strips 23 carries a tab 32 60 which is spaced from the edging strip 24 and makes it possible for the tab 32 to be folded over the top and onto the inner face of the front and rear wall of the box and at the same time clear the edge of the end wall. The cut 65 out portion is outlined by edges 36, 35, 38, 39

and 37, in the manner shown in the drawings. The lines 39 are disposed in such a manner that when the unit 20 is applied to the end face of a box they will constitute extensions of the upper edge of the box. When the unit 20 is applied to the box and the vertical edging strip 23 is folded over along the vertical portion of oblong 25, the material disposed immediately below the edge 39 will serve to cover that portion of the front or rear edge of the end wall that extends above the level of the front or rear wall. The edges 36 are so spaced from each other that the distance between them is substantially equal to the distance between the inner faces of the front and rear walls.

70 The edges 35 are so disposed that when the upper edging strip 24 is folded over the upper edge of the end wall and onto the inner face of the end wall, the edges 35 will abut the upper edges of the front and rear walls, whereby the portion of material that is included between the edges 35 and 38 serves to cover that portion of the inner face of the end wall which immediately overlies the front 75 and rear wall.

75 The manner in which the combined unit 20 is applied to the end face of the box will be appreciated from an inspection of the drawings. The label is applied to the end wall of the box in such a manner that the heavy lines 29 register approximately with the edges of the end wall of the box; the vertical edging strips 23 are then folded over onto the corresponding front and rear walls of the box and the lower portions 34 of the strips 23 are folded over the bottom of the box as shown in Figure 8. The strip 22 is then applied over the bottom of the box. The strip 24 is folded over the upper edge of the end wall of the box and onto the inner face of the end wall of the box, the strip being so designed that the edges 35 will approximately touch the upper edge of the front and rear wall respectively and the edges 36 will approximately touch the inner faces of the front and rear walls respectively. The tabs 32 are folded over the upper edge and inner faces of the front and rear walls respectively and the edges 37 will touch the inner face of the end wall. To provide for clearance these edges 37 are preferably cut on a slight incline, as shown in Figure 4.

80 85 90 95 100 105 110 115 120 125 The portion of the material that is disposed between the lower end of the tab 32 and the heavy line 31 will cover the upper edge of the front and rear wall, whereas the portion that is immediately below the edge 39 covers the upper part of the front and rear edge of the end wall.

130 In order to properly apply the tab 32 it is necessary to sever the material along a line which is an extension of edge 37 and reaching down to the line 31. While it is preferred to prepare the blank in the form

shown and to permit the cut or tear to be made when the blank is applied to the box, a cut along such line may be provided.

The unit 40 that is adapted to cover the

5 front wall of the box is shown in Figure 2.

In view of the fact that in the preferred embodiment as shown in Figures 1 to 9 inclusive the combined units 20 which are de-

10 signed to cover the end walls of the box are

provided with edging strips which overlap onto the front and rear faces of the box, it becomes unnecessary to provide the units which cover the front and rear walls of the box with vertical edging strips. For this

15 reason the combined unit 40 is of very sim-

ple construction and comprises merely an ob-

long strip having printed insignia thereon to provide a label portion 41, a lower edging strip 42 and an upper edging strip 43. The

20 label portion 41 is outlined by the oblong 42a

preferably in a heavy solid color and the length of the unit 40 is substantially less than the length of the box which is indicated in

25 dot and dash outline 44 in Figure 2. The length of the unit 40 is such that when ap-

plied to the front wall of the box and dis-

posed approximately centrally thereof it will overlap the edging strips 23 which have been previously applied to the front and rear walls

30 of the box when the combined units 20 were applied to the end walls of the box.

Like the combined unit 20 the unit 40 may be provided with a heavy line in solid color

45 and another similar line 46 which are in-

35 tended to register with the lower and upper edges respectively of the front wall of the box. Like the combined unit 20 the edging

strips 42 and 43 are also provided with ob-

longs 47 to receive any printed indicia.

40 The application of the unit 40 to the box

is obvious. After the units 20 have been ap-

plied to the end walls of the box as described hereinbefore the unit 40 is applied to the

front wall of the box approximately in such

45 a manner that the lines 46 and 45 register with the upper and lower edges of the front

wall of the box, and the lower portion of the edging strip 42 is folded over onto the

50 bottom of the box whereas the upper portion

of the edging strip 43 is folded over the upper

edge of the front wall of the box and onto the

inner face of the front wall of the box.

The unit 50 shown in Figure 3 of the draw-

ings is designed to be applied to the rear face

55 of the box. In view of the fact that it is

common practice in the manufacture of cigar

boxes to provide a cloth hinge for the attach-

ment of the lid to the rear wall of the box

and in view of the fact that such gummed

60 cloth hinges adhere more firmly to wood than

to paper it is desirable to provide a label for

the rear wall, which will leave the upper

portion of the rear face of the box exposed.

The combined unit 50 comprises the label por-

65 tion 51 and only an edging strip 52 for the

lower corner of the box. The dot and dash outline 53 in Figure 3 shows the relationship between the unit 50 and the rear wall of the box.

In view of the fact that in the finished box 70 an edging strip is applied over the cloth hinge it is preferred to leave the upper edge of the unit 50 in an apparently unfinished form. The label portion 51 of this unit is therefore outlined only on three sides by 75 means of the heavy line 54.

The edging strip 52 is provided with the heavy line 55 which is designed to register with the lower edge of the rear wall of the box and the depending portion 56 of the edg- 80 ing strip is folded over the bottom of the box.

While the embodiment shown in Figures 1 to 9 are the preferred form of the present invention it is obvious that a good many ad-

vantages flowing from the structure shown 85 in such embodiment may also be obtained by various modifications of such structures.

One of such modifications is shown in the em- 90 bodiment illustrated in Figures 10 to 13 in-

clusive. The basic difference between the 95 embodiment shown in these figures and that

shown in the first two sheets of the draw- 99 ings resides in the fact that instead of pro-

viding overlapping portions on the end units 95 such overlapping portions are provided on

the front and rear units.

Under such conditions the end labels 60 be-

come of simple oblong form as shown in

Figure 10 and comprise merely the label por-

tion 61, the upper edging strip 62 and the 100 lower edging strip 63, the horizontal dimen-

sion of the unit 60 being substantially smaller

than the corresponding dimension of the end

wall of the box as shown by the dot and dash

outline 64.

In this modification the combined unit 65

of Figure 11 which is adapted to be applied

to the front wall of the box takes on a form

very much like the form of the combined

unit 20 shown in Figure 4 of the preferred

embodiment. This unit 65 like the unit 20

comprises a label portion 66, two vertical edg-

ing strips 67, a lower edging strip 68 and

an upper edging strip 69. Except for the

fact that the heavy horizontal line 70 in the

vertical edging strips 67 are disposed at a

higher lever than the line 71, the construction

of the unit 65 is identical with that of the

unit 20 in that it also is provided with cut out

portions that have the same functions as the

corresponding portions in the unit 20. The

cut out portions are however, disposed in a

slightly different relationship. The cut out

portions are outlined by the edge 72, 73, 74,

75 and 76. The edges 72 are so disposed that

the distance between them is substantially

equal to the length of the front wall, if the

front vertical edges of the end walls are not

considered a part of the front wall. The re-

130 sult is that when the combined unit 65 is ap-

plied to the front wall of the box and the upper edging strip 69 is folded over the upper edge of the front wall and the upper portion of the inner face of the front wall, the edges 5 72 will substantially touch the inner faces of the end walls.

The edge 73 is so disposed that when the unit 65 is applied to the front wall of the box it will coincide with the top of the front edge 10 of the end walls of the box. The edge 74 is intended to constitute a continuation of the vertical edge 77 of the front face of the box. The portion formed by the edges 74 and 75 is intended to cover that portion of the inner face of the end walls of the box which directly overlies the front wall, whereas 15 as the tabs 78 are also applied to the inner face of the end walls of the box and will be disposed in such a manner that the edge 76 of such tabs will substantially touch the inner 20 face of the front wall of the box.

The combined label and edging unit 80 shown in Figure 12 is designed to cooperate with the combined units 60 and 65 shown 25 in Figures 10 and 11 and to be applied to the rear face of the box. Broadly the unit 80 is identical with the unit 65 in that it is provided with vertical edging strips and the cut out portions that are identical with those 30 shown in the unit 65. In order, however, to provide for the application of a gummed cloth hinge to the bare wood on the rear face of the wall, the upper horizontal edging strip is eliminated and in lieu thereof a pair of 35 tabs 81 are provided, which are adapted to be folded over each end of the upper edge of the rear wall and onto the adjacent portion of the inner face of the rear wall.

The dot and dash line 82 indicates the 40 outline of the rear face of the box and a comparison of the upper edge of this outline with the edge 83 of the label portion of the unit 80 will show that the combined unit 80 is designed to be applied to the rear face in such 45 a manner that the major portion of it reaches to a line spaced below the upper edge of the wall.

The manner in which the combined units shown in Figures 10 to 12 are applied to the 50 box will be apparent from the above description. As distinguished from the manner of application of the preferred embodiment, in this form the front and rear units 65 and 80 are applied to the box first and then the end 55 units 60 are applied to the end walls.

The front and rear units 65 and 80 are applied to the box in the following manner. The unit 65 is applied to the front wall of the box in such a manner that the heavy line 60 71 is in substantial registration with the edges of the front face. The vertical edging strips 67 are turned over to the end faces of the box and then the depending portion of the lower edging strip 68 is applied to the bottom of 65 the box, the corners being applied in the man-

ner in which it is described in the earlier portion of the specification and as shown in Figure 8 of the drawings.

The upper portion of the edging, strip 69 is folded over in such a manner as to cover the 70 upper edge of the front wall of the box and the upper portion of the inner face of the wall. In doing so, however, it is necessary to form a cut of the material along the line that forms an extension of the edge 72. If 75 desired the cut may be provided in the blank for that purpose. The portion of the material immediately below the edge 73 serves to cover that portion of the front edges of the end walls of the box which projects above the 80 front and rear wall of the box.

The portion of the material that is included between the edges 74 and 75 is intended to cover the upper edge of the end walls of the box and also that portion of the inner face of 85 the end walls of the box which immediately overlies the front and rear walls, whereas the tab 78 will project down and be applied to an adjacent portion of the inner face of the end walls of the box in such a manner that the 90 edge 76 abuts the inner face of the front wall of the box.

Unit 80 is applied to the rear wall of the box in a manner similar to 65, the tabs 81 being folded over the upper edge of the rear 95 wall similarly as the portion 69 of unit 65 is folded over the front wall.

After the combined units 65 and 80 are applied to the front and rear walls of the box, the end units 60 are applied to the end walls 100 of the box in a manner that is apparent from the drawings. The upper edging strip will be folded over to cover the upper edge of the end walls and part of the inner face thereof and the lower edging strip will be folded 105 over to cover a part of the bottom wall of the box.

A further modification of a set of combined units is shown in Figures 14, 15 and 16. Figure 14 shows a combined end unit 110 90. The main difference between the combined unit 90 and the combined unit 20 shown in Figure 4 resides in the fact that the tabs 32 shown in the unit 20 are eliminated. In order to show the similarity between the construction shown in Figure 14 and that shown in Figure 4 the same reference numerals as those used in Figure 4 will be applied to corresponding elements.

The upper edging strip 24', it will be seen, 120 is provided with similar cut out portions and its edge formation is such as to provide edges 36', 35', and 38' which function in the same manner as the corresponding edges in the unit 20. The lower corners of the unit 90 125 are preferably cut diagonally as shown at edges 91.

The unit 90 shown in Figure 14 is applied to the end wall of the box in substantially the same manner as the unit 20 of Figure 4. 130

It will be seen however that in view of the fact that the tabs 32 are eliminated, the vertical edging strips 23' will cover the end portion of the front and rear wall of the box and the upper portion of such vertical edging strip will be sufficient only to cover the adjacent upper edge of the front and rear wall of the box.

The combined label and edging unit 92 shown in Figure 15 is designed to cooperate with the unit 90 and to cover the front wall of the box. This unit is simple in construction and its main portion will be applied to the front wall of the box, its length being such that it falls short of covering the entire length of the box. The upper edging strip 93 is somewhat shorter than the main body portion of the unit, its length being such that it is substantially equal to the length of the front wall minus the thickness of the end walls. The edging strip 93 will cover the upper edge of the front wall of the box and part of the inner face thereof. The lower edging strip 94 which is also provided with diagonally cut off corners as shown at 95 is merely folded over and applied to the bottom of the box.

The combined unit 96 shown in Figure 16 is substantially identical in construction with the unit 92 except that it is provided with a cut out portion 97 to permit the application of a cloth hinge to the bare wood. This unit is applied in the same manner as unit 92.

While we have illustrated and described in detail certain preferred forms of my invention, it is to be understood that changes may be made therein and the invention embodied in other structures. We do not, therefore, desire to limit ourselves to the specific construction illustrated, but intend to cover our invention broadly in whatever form its principle may be utilized.

By the term "edging" or "edging strip" appearing in the claims is meant a portion which is applied to a marginal or peripheral part of an outer face of a cigar box which remains exposed when the labeling of the box is completed and which generally bears various indicia such as the tradename of the cigar or the name of the maker of the cigar and/or may bear ornamenting indicia.

What is claimed is:

1. A set of combined labeling and edging units for the lateral walls of a cigar box, said set comprising a combined labeling and edging unit for each lateral wall, the relation between the lengths of such units and the lengths of their corresponding walls being such that the units cooperate to cover cigar boxes of different longitudinal dimensions and insuring registry between the edging and the corners of the box.

2. A set of combined labeling and edging units for the front and end walls of a cigar

box, comprising a combined labeling and edging unit for each end wall and a combined unit for the front wall, the end units being longer than the end wall of the box and the front unit being shorter than the front wall of the box whereby the set is adapted to be applied to boxes of different dimensions.

3. A set of combined label and edging units for the lateral walls of a cigar box, comprising one pair of units adapted to cover a pair of opposing lateral faces, each of said pair of units having portions adapted to overlap onto adjacent portions of the adjacent faces, and each of the other pair being shorter than the corresponding wall.

4. A set of combined labeling and edging units for the lateral walls of a cigar box of the type whose end walls are higher than the front and rear walls, said set comprising in combination a combined unit for one wall, said unit comprising a label and a plurality of edging strips, one of said strips having a portion adapted to overlap onto the adjacent lateral face, and having means for covering the projecting portion of the end wall of the box, and a label and edging unit for the adjacent lateral wall adapted to cover the adjacent face incompletely and overlap onto the above said portion.

5. In combination a set of four combined label and edging units for the lateral faces of a cigar box of the type whose end walls are higher than the front and rear walls, said set comprising a first pair of units for two opposing walls and a second pair of units for the other opposing walls; the units in the first pair each comprising a label, edging means for all adjacent corners, means for covering the portions of the end walls overlying the front and rear walls and edging portions overlying the front and rear walls, and edging portions overlapping on the adjacent lateral wall; and each of the units in the second pair being of smaller length than the length of the corresponding wall, and longer than the distance between the overlapping portions.

6. A combined label and edging unit for a lateral wall of a cigar box of the type having its end walls higher than the front and rear walls, said unit comprising a label portion, a plurality of edging portions and a portion at each end thereof adapted to overlap onto the adjacent face, said unit also having cut out portions adjacent each of the upper corners thereof, said cut out portions cooperating to form one set of vertical edges spaced the external length of the wall, and another set of vertical edges spaced the internal length of said wall, whereby the upper corners of the box may be effectively covered.

7. A combined label and edging unit for a lateral wall of a cigar box of the type having its end walls higher than the front and rear walls, said unit comprising a label por-

tion, a plurality of edging portions and a portion at each end thereof adapted to overlap onto the adjacent face, said unit also having cut out portions adjacent each of the upper corners thereof, said cut out portions being 5 wider at the open end than at the closed end and forming one relatively long vertical edge and two spaced relatively short vertical edges, whereby the upper corners of the box may be effectively covered.

10 8. In combination, a cigar box of the type having its end walls higher than the front and rear walls, and a wrapper for said box comprising a pair of combined label and edging units for said end walls and for the edges 15 of said end walls, a combined label and edging unit for said front wall and for the horizontal edges of said front wall, and combined label and edging unit for said rear wall and its lower horizontal edge, said last named 20 unit reaching only to a line substantially below the upper edge of the rear wall, the front and rear wall units being bounded by four substantially continuous uninterrupted edges.

25 In testimony whereof we have affixed our signatures to this specification.

WILLIAM H. MEYER.
WILLIAM A. JEFSEN.
